(57) CLAIM

The ornamental design for a front panel of a money store, as shown and described.

DESCRIPTION

FIG 1 is a top view of a front panel of a money store showing my new design;

FIG. 2 is a bottom view thereof;

FIG. 3 is a front view thereof;

FIG. 4 is an isometric view thereof;

FIG. 5 is a left side view thereof; and,

FIG. 6 is a right side view thereof.

The drawings are not necessarily drawn to the same scale.

The broken line showing of a money store is included for the purpose of illustrating only and forms no part of the claimed design.

1 Claim, 6 Drawing Sheets
